DANIEL D. SHERWOOD, OF BOSTON, MASSACHUSETTS.

Letters Patent No. 71,798, dated December 3, 1867.

IMPROVEMENT IN MACHINES FOR BUNDLING WOOD.

The Schedule referred to in these Letters Patent and making part of the same.

TO ALL WHOM IT MAY CONCERN:

Be it known that I, DANIEL D. SHERWOOD, of Boston, in the county of Suffolk, and State of Massachusetts, have invented an Improvement in Bundling Wood; and I do hereby declare that the following, taken in connection with the drawings which accompany and form part of this specification, is a description of my invention sufficient to enable those skilled in the art to practise it.

The invention relates to a construction or organization of mechanism for bundling kindling-wood. It is well known that fire-wood, for kindling purposes, is, to a considerable extent, prepared for sale in small quantities ready for use, by sawing the logs into very short and uniform lengths, of from five to eight inches, splitting these pieces into sticks of an inch to two inches in thickness, and tying these sticks into small bundles, each containing perhaps from twenty-five to fifty sticks, the sawing and splitting being mostly effected by machine.

The object of my invention has been to devise a ready means for packing the sticks in round bundles, of uniform size, and for application of the confining-string around each bundle when so packed; and the invention consists primarily in combining with semicircular hoops or jaws, which are bolted together for stuffing the wood between them, springs or mechanism for releasing the wood from the pressure of the jaws when the bundling is effected; also, in arranging two pairs of such jaws with a provision between them for disposing the confining-cord in position, to be drawn around the sticks when they are ready for tying; also, in connecting with the lower jaws a treadle for bringing them together.

The drawings represent a machine embodying the invention—

A showing a front elevation, and B a plan of the same. *a* denotes a bed-piece, supporting, on uprights *b*, a table, *c*. On this table is a frame, *d*, having two cross-shelves *e*, for supporting, in connection with the table *c*, two pairs of semicircular jaws or bands *f*; and in connection with such bands, and for supporting in upright position the collection of sticks to be bundled, each shelf has a circular opening cut through it, made somewhat larger in circumference, however, than the inner circumference of the jaws when closed together. Between the shelves is a space, *g*, which allows the bow or bend in the confining-string to be pressed back beyond the circular opening in the lower shelf, a stop-wall, *h*, being placed upon the shelf, in rear of its opening, to bring the string to position when entered between the shelves. The two jaws of the upper set are hinged, at *i*, to the upper shelf or platform, their front ends being confined together, when the jaws are closed, by a bolt, *k*. Two springs, *l*, spread open the jaws when the bolt is withdrawn, suitable stops being used to determine the extent of opening. The lower jaws are similarly hinged to the table *c*, are confined together by a bolt, *n*, and when released from said bolt, are drawn open by springs *o*. The upper jaws are closed by hand, but as the location of the lower ones does not freely admit of this, provision is made for closing them by foot, this provision consisting in two bent levers, *p*, pivoted beneath the table *c*, and connected by a link, *q*, to a treadle, *r*, the upper arms of the levers bearing against the jaws, so that by depressing the treadle, the jaws will be brought together, as will be readily understood.

The apparatus is operated as follows: The two sets of jaws are first brought together, the upper one by hand, and the lower one by depression of the treadle, and are confined by their respective bolts. Then the confining-cord is thrust in between the shelves, the bend in the cord being guided and stopped by the wall *h*, the two ends of the string being left projecting from the front of the shelf. The sticks of wood are then stuffed endwise into the jaws or rings, as seen in the drawings, until they so completely fill the circular space that no more sticks can be inserted, the lower ends of the sticks coming down upon the table, and being thereby brought into the same plane. The confining-cord is then drawn tightly around the sticks, and the ends are tied. This being accomplished, the bolts are withdrawn, when the springs will instantly throw back the jaws, leaving the tied bundle in condition to be readily removed from the machine.

The apparatus may be located directly beneath a conveying-spout, leading from the sawing and splitting-room, so that the loose wood may be delivered directly upon the machine, and a roadway, *s*, may be arranged on one side of the table *c*, so that, as the bundles are removed from the jaws, they may be deposited upon this roadway, as seen at A, and pressed back, one against the other, that they may drop off at the rear of the table, as will be readily understood.

The arrangement of the parts of the apparatus, as shown, enables the bundling to be rapidly effected in such manner that each bundle shall contain a fixed amount of wood, the clamped jaws acting as inflexible gauges while the bundle is being made up, while, by applying the springs, each end of the bundle is released from the grasp of the jaws when the bolts are withdrawn.

I claim, in combination with the table *c*, the hinged jaws *f*, having bolts for confining them together, and springs for throwing them apart, arranged substantially as and for the purpose set forth.

Also, the arrangement of the two sets of jaws, with the shelf or shelves, and space between, substantially as shown and described.

Also, in combination with the lower jaws and their expanding springs, the treadle, arranged to bring them together, substantially as described.

DANIEL D. SHERWOOD.
